UNITED STATES PATENT OFFICE

FREDERICK T. FEREDAY, OF ANCHORAGE, KENTUCKY, ASSIGNOR TO LOUISVILLE FROG,
SWITCH & SIGNAL CO., OF LOUISVILLE, KENTUCKY, A CORPORATION OF MAINE

TIME SWITCH

Original application filed March 15, 1927, Serial No. 175,616. Divided and this application filed September 25, 1929. Serial No. 395,158.

This invention relates to electric switch devices of the type which are adapted to make or break an electric circuit after the elapse of a predetermined length of time, same being capable of general use but being especially designed for use in connection with flashing time relay mechanisms of the type disclosed in application Serial No. 175,616, of which this application is a division.

10 The general purpose of the present invention is to provide a switch device of the type mentioned which is of simple, inexpensive, durable construction, embodying a minimum number of parts compactly assembled, and 15 which is thoroughly reliable and efficient in use.

More particularly, the invention has in view to provide novel means whereby the period of time elapsing between initiation 20 and completion of the operation of the device may quickly and easily be varied with extreme accuracy.

With the foregoing and other purposes in view, the invention consists in the novel features of construction, combination and arrangement of parts as will be hereinafter more fully described, illustrated in the accompanying drawings and defined in the appended claims.

30 In the drawings, wherein like characters of reference denote corresponding parts in the different views:—

Fig. 1 is a side elevation of a switch device constructed in accordance with the invention.

35 Fig. 2 is a bottom plan view of the structure shown in Fig. 1.

Fig. 3 is a view similar to Fig. 1 with the operating ratchet mechanism removed to more clearly disclose the underlying structure, and also showing the adjusting mechanism of the device in section.

40 Fig. 4 is a section on the line 4—4 of Fig. 3; and

Fig. 5 is a section on the line 5—5 of Fig. 4, illustrating in full and dotted lines, respectively, normal and operated positions of the device.

As illustrated in the drawings, the present switch device, designated generally as C, is mounted upon the lower side of a suitable

support 1 which may be the base of a relay mechanism as disclosed in the aforesaid parent application.

In detail, the device C consists of a bracket 37a of inverted U-shape secured by screws or other suitable fasteners to the underside of the support 1 and inclusive of spaced, depending arms 38 and 39 having a horizontal shaft 36 journaled therein on which is mounted for free swinging movement a frame 44, 55 which, like the bracket 37a, is of inverted U-shape and inclusive of spaced arms 45, 46 disposed between the arms 38 and 39 of said bracket 37a. Journaled in the arms 45, 46, in spaced parallel relation to the shaft 36, is 60 a shaft 43. 65

Loosely mounted on the shaft 36, for rotation with respect thereto, is a ratchet wheel 40 having integral therewith, or otherwise suitably fixed thereto, a pinion 41, while fixed 70 to the shaft 43 and meshing with said pinion 41 is a spur gear 42. Also fixed to said shaft 43 is a pinion 47 which meshes with a spur gear 48 fixed to the shaft 36. Thus, if the gear 48 is held against rotation and rotation 75 is imparted to the ratchet wheel 40, the pinion 41 will produce rotation of the gear 42 which, in turn, will rotate the shaft 43 and the pinion 47 and cause the latter to planetate about the gear 48, resulting in swinging movement 80 of the frame 44 about the shaft 36.

Normally, the frame 44 assumes, under the influence of gravity, or, alternatively, a spring or its equivalent, a depending position with respect to the shaft 36, which position may be predetermined by adjustment of a stop member 57 with which an offset arm 44a of said frame is adapted for engagement. When the ratchet wheel 40 is rotated the frame 44 is adapted to be elevated in the manner stated to cause an abutment 49 carried by one of the arms of said frame to engage and actuate a switch arm 50, thus to change the status of one or more circuits, and when this operation is completed the means for holding the gear 48 against rotation is adapted to be released to permit the frame 44 to return to its normal position.

For holding the gear 48 against rotation electro-magnetic means is provided consist- 100

ing of a magnet 48b and a cooperating armature 48a, the latter being pivoted so as to drop to a predetermined position when the magnet is deenergized and to be lifted upon energization of said magnet to cause a suitably formed finger at the free end thereof to engage a tooth of the gear 48 to hold same against rotation. Thus, a switch which is actuated by elevation of the frame 44 may be 5 in controlling relation to the circuit in which the magnet 48b is included, whereby, upon elevation of said frame, the magnet circuit is opened thereby to permit the armature 48a to drop and release the gear 48 to allow the 10 frame 44 to return to normal position.

Formed as an extension of one of the arms of the brackets 37a is a scale arm 39a curved concentrically with respect to the shaft 36, while adapted for indicating cooperation 15 with this scale arm is a pointer 46a formed at the end of one of the arms of the frame 44 which swings about said shaft 36. Suitable calibrations are provided on the scale arm 39a, and thus, by adjustment of the stop member 20 57 so that the normal or lowermost position of the frame 44 is such as to be indicated by alinement of the pointer 46a with any particular one of said calibrations, the necessary amount of travel of the frame 44 25 from its normal or lowermost position to an elevated switch actuating position may be ascertained at a glance, and, the speed of operation of the ratchet wheel 40 being known, it is a relatively simple matter to adjust the 30 stop member 57 to predetermine the normal position of the frame 44 so that any desired amount of time will elapse between initiation 35 of upward movement of the frame 44 and actuation of the switch arm 50.

40 In the present instance the stop member 57 is in the form of an internally threaded tube mounted for longitudinal movement within a sleeve 53 and held against rotation relative to said sleeve in any suitable manner as, for 45 example, by being provided with an exterior longitudinal groove or channel 56 into which a portion of the sleeve 53 is indented as indicated at 55. The sleeve 53 is disposed in an 50 opening in the support 1 and retained there- 55 in by a flange at its upper end engaging the top of said support and a nut 54 threaded on its lower end engaging the underside of said support. Threaded into the tube 57 and project- 60 ing above the top of the sleeve 53, and 65 there provided with lock nuts 61 to hold it against rotation, is an adjusting screw 58. Formed on this screw is a collar 59 which is disposed between a shoulder formed on the sleeve 53 and a pin 60 carried by said sleeve 66 whereby it is held against longitudinal move- 70 ment but is freely rotatable. Thus, by loos- 75 ening the nuts 61 and rotating the screw 58 the stop tube 57 may be adjusted to predeter- 80 mine the normal or lowermost position of the 85 frame 44, and when the desired adjustment 90 of said tube has been effected said adjustment may be maintained simply by tightening the 95 nuts 61.

Any suitable means for rotating the ratchet wheel 40 may be provided. In the present instance a lever arm 35 is pivoted at one end upon the shaft 36 and carries a pawl 37 for cooperation with the teeth of said wheel, a holding dog 37b pivoted to a suitable fixed support such as the support 1 being provided 75 whereby oscillation of said lever arm is effective to rotate said ratchet wheel intermittently in a single direction, specifically in a direction to effect upward movement of the frame 44. Oscillation of the lever 35 may 80 be effected, for example, by means of the oscillating armature of a flashing signal relay as illustrated in the aforesaid parent application, a portion of such oscillating means being indicated herein generally as B.

From the foregoing description considered in connection with the drawings, it is apparent that with the armature 48a disengaged from the gear 48 the ratchet wheel 40 may be rotated without affecting the switch device 90 C, since the shaft 36 will merely rotate in the bracket 37a. When, however, under predetermined conditions the magnet 48b is energized and the armature 48a thereby moved into holding engagement with the gear 48, 95 oscillation of the lever arm 35 immediately results in elevation of the frame 44 in the manner previously explained, whereby, after the elapse of a predetermined period of time, as determined by the adjustment of the 100 stop tube 57, the switch arm 50 is actuated to make or break a circuit such as the controlling circuit of the relay C and to deenergize the magnet 48b whereby operation of the relay C is stopped and the frame 44 is permitted 105 to return to its normal position in readiness to complete the operation when the magnet 48b again is energized.

Without further description, it is thought that the features and advantages of the invention will be readily apparent to those skilled in the art, and it will, of course, be understood that changes in the form, proportion and minor details of construction may be resorted to, without departing from 110 the spirit of the invention and scope of the appended claims.

I claim:

1. In mechanism of the class described, a switch, a pivoted member adapted by swing- 115 movement to actuate said switch, a pair of intermeshing gears one of which is carried by said member and the axis of the other of which is coincident with the pivotal axis of said member, means for rotating said first mentioned gear wheel, means for holding 120 said second mentioned gear wheel against rotation whereby rotation of said first mentioned gear wheel results in switch actuating swinging movement of said mem- 125 ber.

ber, a fixed scale element, a pointer carried by said pivoted member for cooperation with said scale element, and means for variably predetermining the effective range of movement of said pivoted member.

2. In mechanism of the class described, a support, a frame element fixed to said support, a scale element carried by said frame element, a switch, a member pivoted to said frame element and adapted by swinging movement to actuate said switch, a pair of intermeshing gears one of which is carried by said frame element and the axis of the other of which is coincident with the pivotal axis of said member, means for rotating said first mentioned gear wheel, means for holding said second mentioned gear wheel against rotation whereby rotation of said first mentioned gear wheel results in switch actuating swinging movement of said member, a pointer on said member for cooperation with said scale element, and an adjustment screw carried by said support and constituting an abutment engageable by a portion of said pivoted member to predetermine the normal spacing of the latter from the switch.

3. In mechanism of the class described, a switch, a fixed bracket, a shaft rotatably mounted in said bracket, a pair of gear wheels one of which is fixed and the other loose on said shaft, a member pivoted on said shaft and adapted by swinging movement to actuate said switch, a shaft carried by said member, a pair of gears fixed to this last mentioned shaft and meshing with said first mentioned pair of gears, respectively, means for rotating said loose gear, and means for holding the gear which is fixed to said first mentioned shaft against rotation whereby rotation of said loose gear produces swinging movement of said member.

In testimony whereof I hereunto affix my signature.

45 FREDERICK T. FEREDAY.
